Harold D. Penney

ATTORNEY

UNITED STATES PATENT OFFICE.

WILLIAM J. KATTREIN, OF ALBANY, NEW YORK.

ADJUSTABLE PILOT REAMER.

Application filed March 28, 1927. Serial No. 178,973.

- This invention relates to pilot reamers or alining reamers and more particularly to expansion reamers having self adjusting spring pilots thereon for alining the reamer, 5 as when reaming and alining worn piston wrist-pin holes, though it is noted that the invention is not limited to reamers for use with spring alining pilots nor in some respects even to pilots.
- 10 One object of the invention is to provide an expansion-pin actuated reamer having a one-piece body including a suitable forward shank for the reception of a sliding adjustable pilot.
- 15 Another object of the invention is to provide a reamer of this kind in which the bore for the expansion pin does not pass through said shank, but passes through the rear tool-receiving end of the body.
- 20 Another object of the invention is to provide a reamer of this kind in which danger of rupture through over expansion is eliminated.
- Other objects of the invention are to improve generally the simplicity and efficiency of such reamers and to provide a reamer of this kind which is easy to operate, economical, durable and reliable in use, and easy and economical to manufacture.
- 30 Still other objects of the invention will appear as the description proceeds; and while herein details of the invention are described and claimed, the invention is not limited to these, since many and various changes may be made without departing from the scope of the invention as claimed in the broader claims.
- The inventive features for the accomplishment of these and other objects are shown 40 herein in connection with an improved reamer which, briefly stated, includes a one-piece body provided with a rear tool receiving part, a forward long shank and an axial bore extending through said rear part and terminating near the rear of said shank. Said body is intermediately provided with long outwardly expansible cutting flutes, and openings therebetween extending into said bore throughout the major part of the flutes.
- 45 An expanding pin received in said bore has its motive end at said tool receiving part and has expanding engagement with intermediate parts of said flutes. While various proportions are possible said shank may be 50 about as long as said flutes, about half the diameter of the fluted portion and less than twice the diameter of said pin, thereby adapting it for the slidable reception of a pilot having an outside diameter suitably approximating that of the fluted portion. 60
- In the accompanying drawing, showing by way of example, one of many possible embodiments of the invention,
- Fig. 1 is a side elevation showing the reamer with pilot thereon as in use reaming out the wrist-pin holes of a piston, the piston being shown in axial section;
- Fig. 2 is a longitudinal sectional view, partly in elevation, showing the reamer with the pilot thereon, the section being taken on a slightly twisted plane; and
- Fig. 3 is a side elevation of the pilot.
- My improved reamer comprises a body portion provided at the rear and motive end with a squared tool receiving head 5. Adjacent to said head is a long cylindrical rear pilot 6, and at the forward end there is a smooth forwardly extended cylindrical shank 7 of uniform diameter about half the diameter of the rear pilot 6.
- Said body portion is also provided with an axial bore 10 (Fig. 2) enlarged and threaded, as at 11, at the motive end of the reamer and tapering intermediately, as at 12, toward the leading end and terminating, 80 as at 13, near the rear end of said shank 7.
- The intermediate part of said body portion between said shank and rear pilot is provided with long and spiral flutes 15 provided with forward cutting edges 16. Elongated cuts 17 are provided in the bottom of the groove between said flutes and extend into said bore 10 throughout the length of said flutes and the tapered portion 12, thereby forming elongated slightly outwardly 90 yieldable expanding sections. A small portion of the reamer at the ends of the flutes are slightly reduced to form necks 18 and 19.
- In said bore 10 is disposed an expanding pin 20 having its rear end portion 21 enlarged and in threaded engagement with the threads 11 of said bore and provided with a flattened tool receiving end 22 projecting to the rear of said squared heads. The forward end 23 of said pin is tapered and engages said expanding sections at the tapered portion 12 for forcing the flutes 15 outwardly to adjust the diameter of the active portion of the reamer. 100
- A limiting collar 25 fast on the projecting end 21 of said pin limits the inward move-

ment of the pin to prevent excessive expanding of the reaming portion and breakage of said expanding sections and flutes. On said shank 7 is disposed a pilot 27 serving for guiding said reamer into, or alining the reamer with, a hole of irregular or other cross-section, such for instance as the hole 29 of a piston 30 having the wrist-pin holes 29 and 31, which it is desired to ream out 10 and aline.

Said pilot is here shown as comprising a body portion 33 provided with a bearing bore 34 fitting on said shank 7. A plurality of resilient fingers 35 formed on the inner 15 end of said body portion are spaced from said shank and pointed toward the reamer. The outer face of said fingers being formed near the free ends of the fingers with bead-like portions 36 respectively engageable with 20 the intermediate part of the interior of the hole 29 for substantially centering the reamer with that part, the intermediate part 37 of the outer face of said fingers being converged, when the fingers are sprung in, 25 to provide a conical portion adapted to wedge in the end of the hole 29 for substantially centering the hole at said part, whereby by centering the reamer at said two parts 36 and 37, the reamer is substantially alined 30 with the axis of the hole.

In order to accommodate the pilot 27 or other similarly operative pilot, said shank 7 is here shown as being about as long as said flutes 15, about half the diameter of the 35 fluted portion and less than twice the diameter of the pin 20 which makes it enough smaller in diameter than the flutes to receive the expanding pilot 27 slidably on said shank and still leave room for an outside 40 effective diameter approximately that of the fluted portion; but in order for the pilot to be practically operative, the shank 7 has to be so small that it would be difficult and costly to provide a bore such as the bore 10 therethrough such as could receive the pin 45 20 and enlargement 21. It was for a long time thought impossible to use the herein shown type of expanding reamer with the forward shank and spring pilot because of 50 the difficulty of providing the long forward bore; and it was decided to use this shank and pilot with the inferior Critchley type of reamer shown in U. S. Patent No. 51,563 of Dec. 19, 1865. The problem was long 55 known and the solution sought, but the solution was long deferred because no one of the inventors and mechanics consulted thought of having the shank 7 free of bore and the pin 20 manipulated from the rear 60 end. The herein invention solves the problem.

The operation of the reamer on piston wrist pin holes is simple and obvious. By means of the flattened end 22 the flutes are 65 set to the required diameter for initial ream-

ing. The pilot is removed; the shank 7 is inserted through one wrist pin 31 into the hole 30; the pilot is replaced with the beaded end inward, the beaded end initially centering the shank 7, and then the pilot is pressed 70 inward with a wedging fit, the beads 36 engaging near one end of the hole 29, the intermediate part 37 of the fingers engaging the outer end. This alines the reamer with the hole 29, and the hole 31 is then reamed by 75 the reamer in alinement with the hole 29 the shank 7 sliding and turning in the pilot, as the reamer moves toward the hole 29 and commences to ream it. The pilot is then removed and both holes reamed in alinement 80 with each other.

Other uses for the reamer, besides spaced apart alined holes, will readily suggest themselves; and as both end portions of the holes are engaged by the bead and intermediate 85 portion of the fingers, the reamer is useful for reaming out single holes which are not to be alined with other holes.

I claim as my invention:

1. In a reamer, a one-piece body portion 90 provided with a rear tool receiving head and at the forward end with a long smooth cylindrical shank of constant diameter; said body portion having an intermediately forwardly tapered axial bore extending from, 95 and threaded at, said rear end, and terminating to the rear of said shank; said body portion between said shank and rear head being provided with long cutting flutes and cuts therebetween extending into said bore throughout the length of the flutes and said tapered portion; said shank being smaller in diameter than the fluted portion; an expanding pin in threaded engagement with the threads of said bore and provided with a projecting tool-receiving rear end, the forward end being tapered and engaging the tapered portion of the bore; and an automatically expanding spring pilot guide provided with a bearing bore slidably fitting 100 on said shank.

2. In a reamer, a one-piece body portion provided with a rear tool receiving head and at the forward end with a long smooth cylindrical shank of constant diameter; said body portion having an intermediately forwardly tapered axial bore extending from, and threaded at, said rear end, and terminating to the rear of said shank; said body portion between said shank and rear head 115 being provided with long cutting flutes and cuts therebetween extending into said bore throughout the length of the flutes and said tapered portion; said shank being smaller in diameter than the fluted portion; an expanding pin in threaded engagement with the threads of said bore and provided with a projecting tool-receiving rear end, the forward end being tapered and engaging the tapered portion of the bore; and a pilot 120 125

guide provided with a bearing bore slidably fitting on said shank.

3. In a reamer, a body portion provided with a rear tool receiving head, a long cylindrical rear pilot adjacent to said head and at the forward end with a long smooth cylindrical shank of constant diameter; said body portion having an intermediately forwardly tapered axial bore extending from, 10 and threaded at, said rear end, and terminating to the rear of said shank; said body portion between said shank and rear pilot being provided with long cutting flutes and cuts therebetween extending into said bore 15 throughout the length of the flutes and said tapered portion; the fluted portion being substantially the diameter of the rear pilot, and said shank being smaller in diameter than the rear pilot and the fluted portion 20 and less than twice the diameter of said bore; an expanding pin in threaded engagement with the threads of said bore and provided with a projecting tool receiving end, the forward end tapered and engaging the 25 tapered portion of the bore; and a pilot slideable on the shank.

4. In a reamer, a body portion provided with a rear tool receiving head, and at the forward end with a long smooth cylindrical shank of constant diameter; said body portion having an intermediately forwardly tapered axial bore extending from, and threaded at, the rear end, and terminating just to the rear of the shank; said body portion between said shank and rear head being provided with long cutting flutes and cuts therebetween extending into said bore throughout the length of the flutes and tapered portion; said shank being smaller in 40 diameter than the fluted portion and less than twice the diameter of said bore; an expanding pin in threaded engagement with the threads of said bore and provided with a rearwardly projecting tool receiving end, 45 the forward end being tapered and engag-

ing the tapered portion of the bore; and an automatically expanding spring pilot guide comprising a body portion provided with a bearing bore slidably fitting on said shank, and spring fingers formed on the inner end 50 of said body portion and spaced from said shank and pointing toward the reamer, the free ends of said fingers being formed with bead-like outer portions to form a resilient annular bead around the guide, the outer 55 faces of said fingers being converged when the fingers are converged to form an intermediate resilient conical portion as large in diameter as said bead.

5. In a reamer, a body portion provided with a rear tool receiving head, a long cylindrical rear pilot adjacent to said head and at the forward end with a long smooth cylindrical shank of constant diameter; said body portion having an intermediately forwardly tapered axial bore extending from, and threaded at, said rear end, and terminating to the rear of said shank; said body portion between said shank and rear pilot being provided with long cutting flutes and 60 cuts therebetween extending into said bore throughout the length of the flutes and said tapered portion; said shank being smaller in diameter than the rear pilot and the fluted portion and less than twice the diameter of 65 said bore; an expanding pin in threaded engagement with the threads of said bore and provided with a projecting threaded and flattened tool receiving end, the forward end tapered and engaging the tapered 70 portion of the bore; a collar fast on the projecting threaded end of said pin for limiting inward movement of the pin and excessive expanding of the flutes; and a pilot 75 slideably snugly fitting on said shank. 85

Signed at Albany, in the county of Albany and State of New York, this 21st day of March, A. D. 1927.

WILLIAM J. KATTREIN.
